UNITED STATES PATENT OFFICE.

GEZA GREENBERG, OF NEW YORK, AND KURT STOYE, OF FLUSHING, NEW YORK, AS-
SIGNORS TO THE KNY-SCHEERER CORPORATION OF AMERICA, OF NEW YORK,
N. Y., A CORPORATION OF NEW YORK.

URETHROSCOPE.

Application filed September 27, 1923. Serial No. 665,067.

To all whom it may concern:

Be it known that we, GEZA GREENBERG and KURT STOYE, both citizens of the United States, residing, respectively, at New York city, county of New York, State of New York, and Flushing, Long Island, county of Queens, State of New York, have invented certain new and useful Improvements in a Urethroscope, of which the following is a specification.

This invention relates to an improvement in a urethroscope and the novelty consists in the adaptation and arrangement of parts as will be more fully hereinafter pointed out.

This device is particularly an improvement of the urethroscope of Greenberg & Winter described and claimed in United States Letters Patent No. 1,453,975, of May 1, 1923, and reference may be made to that patent to cover the general operation of urethoscopes.

Great difficulty has been found in the use of urethoscopes in looking into the bladder cavity or other cavity to be examined because of the lack of an adjustable telescope which difficulty our device has overcome by combining with a urethroscope a collapsible telescope which can be swung into position for use when desired or swung out of position so as to be out of the way as may be required, and also be detachably removed.

Another handicap in the use of urethoscopes has been in the failure to eliminate bubbles occurring in the water which is used to inflate the organ to be examined, and which obstruct the vision of the operator. Our device has overcome this difficulty and furnishes means of ready elimination of such bubbles without disturbing the urethroscope and other instruments therein during the operation.

Our device also furnishes an eccentric coupling thereby permitting the use of various sizes of tubes without losing the alignment necessary for sighting through the eye piece of the urethroscope.

Our device also furnishes a more perfect connection for the lighting means so as to secure perfect contact under all conditions, and also embodies a sliding depth gauge which enables the operator to definitely determine the depth of the insertion of the

urethroscope and to definitely determine the exact amount it must be moved where a change is required.

Referring to the drawings, Fig. 1 is a top plan view of our improved urethroscope which has been broken for convenience in illustration, and which shows the collapsible telescope swung out of position as when not in use, and showing it in position for use in dotted outline;

Fig. 2 is a vertical section of our complete device;

Fig. 3 is a vertical section of the eccentric coupling; and

Fig. 4 is an end view of Fig. 3 looking in at the right;

Fig. 5 is a detail of the light carrier;

Fig. 6 is a cross section of the air outlet 70 and eye piece; and

Fig. 7 is a detail of an alternative spring valve to be used as an air outlet.

8 is a urethral tube to which is secured an eccentric coupling 9 and a main body 10 of our device is adapted to be rigidly secured to said coupling 9 in which there is a water inlet 11 having a valve 12 controlling the same. Eye piece 13 is also rigidly mounted in the body 10 and has the usual lens 14.

In the eye piece 13 there is also mounted in flange 15 a set screw 16 of usual construction and which is adapted to serve as an outlet for air bubbles forming in space 17 on the inside of the lens 14. A collapsible telescope 18 of usual construction is mounted on the body 10 by means of a bracket 19 which is removably secured to a screw clamp 20, the base of which is integral with the body 10.

A sliding depth gauge 21 is mounted on the tube 8 and has a slot 22 permitting the operator to see divisional marks 23 on the tube 8 so that the sliding shield 21 can be moved to the exact position which is to locate it so as to serve as a depth gauge for the insertion of the tube 8. Through the base of the body 10 a lighting wire 24 of usual construction is adapted to be mounted so as to pass through a lighting tube 25 which is adapted to lie along the base of the inside of the tube 8. The lighting tube 25 terminates in an internal threading 26 into which is adapted to be threaded a container member 27 having an opening 28 and in which

is adapted to be mounted a plate 29 over which is adapted to be mounted a spring 30 and a sliding member 31 is adapted to be mounted so as to ride on said spring in an 5 opening 32 in the opposite end of the container member 27 from the opening 28. A lamp 33 of usual construction having a threaded socket 34 is adapted to be mounted in the internal threading 26 until a contact 10 nipple 35 at the base of said socket 34 is registered in contact with the sliding member 32. This construction assures the contact of the wire 24 with the plate 29 and through the spring and sliding member 31 always ensures 15 contact with the contact nipple 35 in spite of variations which might otherwise break the contact were it not for the sliding member 32 which under spring pressure 30 will always ride up into contact with the contact nipple 35, thus assuring a light during 20 the entire operation and eliminating the possibility of the failure of the light through the breaking of the contact.

The eccentric nipple 9 has a boring 36 25 which is eccentric so as to assure the alignment of the lens 14 and telescope 18 so that the vision of the operator will always be clear through the tube 8 and so that the lighting tube 25 will always lie at the base 30 out of the way of possibility of obstructing the vision of the operator. A larger tube is noted in dotted outline as 37 in Fig. 4 thus 35 always assuring the largest possible amount of unobstructed space through the tube 8 for the vision of the operator.

Figs. 6 and 7 show further modifications or alternative forms for the air outlet in which, as is shown in Fig. 6, a nipple 38 has an internal threading 39 adapted to 40 screw into an internally mounted boring 40 in the eye piece 13, said nipple 38 having an internal threading 41 in which the screw 42 is adapted to be seated so as to control the outlet 43 in the nipple 38. Fig. 7 shows a 45 spring valve member having a base 44 adapted to be rigidly mounted in the eye piece 13 having a valve seat 45 in which a valve 46 is adapted normally to seat under pressure of spring 47, said base 44 having 50 an outlet 48 so that air or bubbles formed in chamber 17 may pass out through said valve 44 when it is open, or through valve 42 when it is open, or through valve 16 when it is open, these three being alternative forms of 55 valves. In using this device the tube 8 will be inserted into the urethra in the usual way and the bladder will then be distended by turning on the water inlet 11, which is controlled by valve 12, until the bladder is 60 sufficiently distended. The operator can then swing the telescope 18 into position for observation and the light 33 will illuminate the cavity being examined so that the operator can use the instrument desired upon removing eye piece 13 and if the telescope 18

is in the way it can be swung to one side temporarily or it can be readily removed. The light 33 will not flicker and vary because of imperfect contact but will burn steadily as the contact will always be maintained steadily by the sliding member 31 which insures a positive perfect contact in spite of any variation which may be caused by jars or movement of parts. Also by 70 opening air pressure valves 16, 42 or 44 which can be easily and quickly done by the operator without disturbing the operation, all bubbles gathering on the inside of lens 14 may be eliminated thereby assuring a clear vision at all times.

It will be understood that although this device is called a urethroscope, it is also adapted to be used in the other natural body openings and the use of such name is not intended to in any way limit the scope of the 85 invention.

We claim:

1. In a urethroscope, the combination of a urethral tube having an external scale thereon, an eccentric coupling, an eyepiece, 90 a water inlet means, an air outlet valve, a collapsible telescope removably and adjustably attached to the body of said urethroscope and a sliding depth gauge mounted on said tube.

2. In a urethroscope, the combination of a urethral tube having an external scale thereon, an eccentric coupling, an eyepiece, a water inlet means, an air outlet valve, a collapsible telescope removably and adjustably attached to the body of said urethroscope, a sliding depth gauge mounted on said tube, and means for lighting the distal end of said tube.

3. In a urethroscope adapted for water inflation of the organ to be examined, a tube having an external scale thereon and a sliding depth gauge mounted on said tube, a collapsible telescope secured to the body of said urethroscope so that it can be readily swung into or out of position for use and be readily removed therefrom and means for lighting the distal end of said tube.

4. In a urethroscope, the combination of a urethral tube having an external scale thereon, an eccentric coupling, an eyepiece, a water inlet, an air outlet valve, a collapsible telescope removably and adjustably attached to the body of said urethroscope and a sliding depth gauge mounted on said tube, and means for lighting the distal end of said tube comprising a bulb connected to the power wire by a slidale member under constant spring pressure against the contact point in the socket of said bulb.

5. In a urethroscope adapted for water inflation of the organ to be examined, a tube having an external scale thereon and a sliding depth gauge mounted on said tube, a

collapsible telescope secured to the body of said urethroscope so that it can be readily swung into or out of position for use and be readily removed therefrom, and means for lighting the distal end of said tube comprising a bulb connected to the power wire by a slidale member under constant spring

pressure against the contact point of said bulb, said spring resting on a plate in contact with said power wire. 10

In testimony whereof we affix our signatures.

GEZA GREENBERG.

KURT STOYE.
